C. T. WESTLAKE.
LOCOMOTIVE BUFFER BEAM.
APPLICATION FILED APR. 16, 1917.

1,233,153.

Patented July 10, 1917.

UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE BUFFER-BEAM.

1,233,153.

Specification of Letters Patent. Patented July 10, 1917.

Application filed April 18, 1917. Serial No. 162,403.

To all whom it may concern:

Be it known that I, CHARLES T. WESTLAKE, a citizen of the United States, residing at St. Louis, in the State of Missouri, 5 have invented a new and useful Improvement in Locomotive Buffer-Beams, of which the following is a specification.

My invention relates particularly to the openings usually formed through the top member or wall of a metallic buffer-beam for lightening the beam and providing access to its interior.

It has been found in practice that these openings are a source of danger to the operator from the liability of his feet catching therein and so causing him to trip, and my invention has for its object to eliminate this danger.

It consists in protecting the said openings by gratings as hereinafter described and claimed, reference being had to the accompanying drawing forming part of this specification, whereon,

Figure 1, is a top plan view of a locomotive buffer-beam constructed according to my invention; Fig. 2, a similar view to Fig. 1 of the beam showing an alternative form of the improvement, and Fig. 3, a cross section through the beam on line 3, 3, 30 in Fig. 1.

Like letters and numerals of reference denote like parts in all the figures.

Referring particularly to Figs. 1 and 3, *a* represents my improved locomotive buffer-beam which is preferably, in the present case rectangular box-shaped in cross section of cast steel integral throughout.

Within the beam *a*, at each side of the longitudinal center of the locomotive frame 40 and transverse center *x* of the beam *a* is preferably arranged a diagonal brace *b* which unites with and diverges from the front wall 1 of the beam *a* to the rear wall 2 of the beam *a* at the connection therewith of the corresponding longitudinal member 3 of the said frame.

Copies of this patent may be obtained for five cents each, by addressing the "Commissioner of Patents, Washington, D. C."

In carrying out my invention, each opening usually formed through the top member or wall 4 of the beam *a* at each side of its transverse center line *x*, and the configuration of which in the present case is indicated by the heavy broken lines *c* and *d* respectively, is covered by a grating consisting of a plurality of intersecting bars 5 forming preferably, rectangular-shaped 55 interstices 6 which with the bars 5 are suitably arranged to conform collectively as nearly as practicable to the shape of the space inclosed by the lines *c* and *d* respectively, the division bars 5, at the lines *c* and *d* being united integrally with the top member 4 of the beam *a* as shown; it being noted in this connection, that the sides of the lines *c* and *d* preferably conform to the direction of the diagonal braces *b*, front 65 wall 1, and rear wall 2 respectively, of the beam *a*.

Or in lieu of rectangular-shaped interstices 6 as described, circular-shaped interstices 6' may be used as seen in Fig. 2; or 70 the interstices of the gratings may be of any other shape as found most suitable. Moreover, each grating so formed and arranged in lieu of being integral with the top member 4, may be separate therefrom 75 and fixed thereto around and conformably to the lines *c* and *d* in any suitable manner, and in this connection it is to be noted that, the same principle and construction of grating may be applied to any other form 80 of opening through the top of a buffer-beam or end sill, and analogous to the openings indicated by the lines *c* and *d*.

I claim:

1. In a buffer-beam of the character described having an opening through the top, a grating adapted to form a cover to the said opening.

2. A buffer-beam of the character described having perforations through the top 90 adapted to form a grating.

CHARLES T. WESTLAKE.
